CLAIM

The ornamental design for a headboard, as shown and
described.

DESCRIPTION

FIG. 1 is a front elevational view of a headboard, showing
my new design, the rear being identical thereto;
FIG. 2 is a side elevational view, the opposite side being
identical thereto;
FIG. 3 is a top plan view; and,
FIG. 4 is a bottom plan view thereof.

FIG. 2

FIG. 1

FIG. 3

FIG. 4
